Filed Mar. 23, 1964, Ser. No. 79,109

Term of patent 14 years

(Cl. D72—1)

FIG. 1

FIG. 2

FIG. 3

FIG. 4

FIG. 5

FIG. 1 is a front elevation of a revolving safety reflector signal, showing my new design;

FIG. 2 is a side elevation view thereof;

FIG. 3 is a top view thereof;

FIG. 4 is a top view showing the upper section in an angular position relative to the bottom section; and

FIG. 5 is a bottom view of the revolving safety reflector signal.

The wire support legs are fragmentarily shown in FIGS. 4 and 5 for convenience of illustration only.

The undisclosed rear is the same in appearance as the front with the exception that there is no switch.

I claim:

The ornamental design for a revolving safety reflector signal, as shown and described.
